UNITED STATES PATENT OFFICE.

WILLIAM MORRIS AUSTIN, OF ELIZABETH, NEW JERSEY.

BOLT-BOARD.

1,232,171.

Specification of Letters Patent.

Patented July 3, 1917.

Application filed November 28, 1916. Serial No. 133,906.

To all whom it may concern:

Be it known that I, WILLIAM M. AUSTIN, a citizen of the United States, and a resident of Elizabeth, in the county of Union 5 and State of New Jersey, have invented a new and Improved Bolt-Board, of which the following is a full, clear, and exact description.

The object of the invention is to provide 10 a new and improved bolt board more especially designed for winding thereon textile fabrics having embroidered borders or other thickened portions and arranged to compensate for the increased thickness in 15 the embroidered portions with a view to provide a bolt approximately uniform in thickness throughout its length.

In order to accomplish the desired result, use is made of a bolt board having one end 20 portion reduced in thickness to accommodate the thickened portion of the fabric.

A practical embodiment of the invention is represented in the accompanying drawings forming a part of this specification, in 25 which similar characters of reference indicate corresponding parts in all the views.

Figure 1 is a perspective view of the bolt board;

Fig. 2 is a plan view of the same;

30 Fig. 3 is a sectional side elevation of the same with the flexible fabric wound thereon;

Fig. 4 is a perspective view of a modified form of the bolt board;

Fig. 5 is a side elevation of the same;

35 Fig. 6 is a plan view of the same;

Fig. 7 is a side elevation of a double bolt board;

Fig. 8 is a similar view of another modified form of the bolt board; and

40 Fig. 9 is a plan view of the same.

In winding textile fabrics, having embroidered borders or like thickened portions at one side, onto a bolt board of uniform thickness, the embroidered or thickened portions render the bolt thicker at one end than on the other, and hence the bolt does not present a neat appearance, and in packing and shipping takes up more room than necessary. In order to overcome these objectionable features and to render the bolt approximately uniform in thickness throughout its length, use is made of a bolt board presently described in detail.

As shown in Figs. 1, 2 and 3, the bolt

board consists of a main piece 10, of card- 55 board, wood or other suitable material, and the main piece 10 is overlaid at opposite side by body pieces 11 and 12 extending from one end of the main piece 10 to within a distance of the other end of the main 60 piece 10 so as to leave a portion of the bolt board thinner at one end than at the remaining portion to accommodate embroidered borders 13 or the like in the textile fabric wound upon the bolt board in the 65 usual manner, as will be readily understood by reference to Fig. 3. The body pieces 11 and 12 are attached to the main piece 10 in spaced relation thereto by crossbars 15, 16 and 17, of which the crossbars 15 and 16 70 are adjacent the ends of the body pieces 11 while the crossbar 17 is intermediate the crossbars 15 and 16.

In practice, the body pieces 11 and 12 are inclined toward each other from the outer 75 end to the inner end thereof so as to render the body of the bolt wedge-shaped, as will be readily understood by reference to Figs. 1 and 3, it being understood that for the purpose mentioned the crossbars 15, 16 and 80 17 are made correspondingly thinner, that is, the outermost crossbar 15 is thickest, the crossbar 17 is somewhat thinner than the crossbar 15, and the crossbar 16 is thinner than the crossbar 17. 85

The body pieces 11 and 12 as well as the corresponding opposite portions of the main piece 10 are tapered on the inner end to the outer end thereof, as plainly shown in Fig. 2, to compensate for the increase in thickness 90 of the outer end of the bolt board to insure uniform winding of the textile fabric on the bolt board.

Usually the embroidered portion does not extend to the very edge of the fabric, and in order to accommodate this embroidered outer edge use is made of crossbars 20 attached to the free end of the main piece 10 at opposite sides thereof. By reference to Fig. 3, it will be noticed that when the textile fabric 14 is wound up on the bolt board it is uniform in thickness throughout its length thus forming a neat package which can be readily packed in suitable cases, envelopes or the like. 105

In the modified form shown in Figs. 4, 5 and 6, the body piece 12 with the corresponding crossbars 15, 16, 17 is omitted, and in

this case the main piece 25 is overlapped on one side by a body piece 26 resting at its side on tapering strips 27 to which both pieces 25 and 26 are fastened by glue, nails 5 or other fastening devices. The body piece 26 terminates a distance from one outer end of the piece 25 and the outer end of this main piece 25 extends beyond the body piece 26. A crossbar 28, similar to the one on the 10 bolt board shown and above described with reference to Figs. 1, 2 and 3, is used.

Two bolt boards, such as shown in Figs. 4, 5 and 6, may be placed back to back to form a double bolt board, as illustrated in 15 Fig. 7.

In the modified form shown in Figs. 8 and 9, the main piece 30 is overlaid by a body piece 31 fastened at its outer end by a crosspiece 32 to the corresponding end of the 20 body piece 30, and the inner end of the body piece 31 is fastened by staples or other fastening means 33 to the body piece 30. The pieces 30 and 31 are tapering the same as above described in reference to the bolt board 25 shown in the preceding figures.

Having thus described my invention, I claim as new and desire to secure by Letters Patent:—

1. A bolt board adapted to have a fabric 30 with a thickened portion wound thereon, said board having a longitudinally tapering body terminating in an end portion reduced in thickness.

2. A bolt board adapted to have a fabric 35 with a thickened portion wound thereon, said board having a longitudinally tapering body terminating in an end portion reduced in thickness and provided at its free end with a crossbar.

40 3. A bolt board, upon which a fabric having a thickened portion is adapted to be wound, comprising a main piece of uniform thickness, and a body piece overlying the main piece and terminating a distance from

one end thereof, whereby one end of the 45 board will be reduced in thickness.

4. A bolt board upon which a fabric having a thickened portion is adapted to be wound, comprising a main piece, a body piece of less length than the said main piece, 50 the said pieces being wedge-shaped, and cross-bars connecting the said body piece with the said main piece.

5. A bolt board upon which a fabric having a thickened portion is adapted to be 55 wound, comprising a main piece, a body piece of less length than the said main piece, the said pieces being wedge-shaped, cross-bars connecting the said body piece with the said main piece, and a crossbar attached to 60 the free end of the said main piece.

6. A bolt board, comprising a main piece tapering at the sides, and a body piece overlying the said main piece and similarly tapered at 65 the sides, the said body piece terminating a distance from the widest end of the said main piece.

7. A bolt board, comprising a main piece tapering at the sides, a body piece overlying the said main piece and similarly tapered at 70 the sides, the said body piece terminating a distance from the widest end of the said main piece, and connecting bars connecting the said main piece and the said body piece with each other and holding the same spaced 75 apart.

8. A bolt board, comprising a main piece tapering at the sides, a body piece overlying the said main piece and similarly tapered at 80 the sides, the said body piece terminating a distance from the widest end of the said main piece, connecting bars connecting the said main piece and the said body piece with each other and holding the same spaced 85 apart, and a crossbar on the widest end of the said main piece.

WILLIAM MORRIS AUSTIN.
